Fig. 2.

The image shows the front cover of a book. The title 'Inventor' is written in a large, decorative, cursive font at the top. Below it, 'George Long' is written in a smaller, more formal font. At the bottom, the publisher's name 'William Clowes & Sons' is written, followed by 'London' and '1855'. The price '50' is printed in the top left corner. The book is bound in dark brown leather with gold-tooled decorations on the spine and corners.

UNITED STATES PATENT OFFICE

2,181,603

BAG HANDLING MECHANISM

George Long, Joliet, Ill., assignor to Franklin Steel
Works, Joliet, Ill., a corporation of Maine

Application August 19, 1937, Serial No. 159,876

11 Claims. (Cl. 226—56)

The invention relates to bag handling mechanism and has reference particularly to mechanism for use in bag closing machines for adjusting the bags to their proper pack height determined by the material within the bag.

In bag machines of the fully automatic or semi-automatic type various operations are performed on the bags as they progress from station to station throughout the machine. Before the bags can be presented to the station having mechanism for closing the open end of the bag, it is necessary, especially if a tight pack is desired, to adjust the height of the bag. The level of the material in the bags will vary somewhat even when all the bags passing through the machine contain the same material in the same condition, as, for example, coffee beans that have been ground to a uniform degree of fineness. Therefore best results in producing a tight pack are secured by accurately gauging the upper level of each bag by the contents within the respective bag.

An object of the invention therefore is to provide improved means which will operate in a novel manner to first elevate the bags to an initial pack height which may be adjusted to suit the particular material passing through the machine and which will then automatically gauge the upper pack level of the bags individually.

A more specific object of the invention resides in the provision of novel mechanism having location in advance of the bag closing means for elevating the bags to an initial pack height and in the provision of automatic means having association therewith for additionally elevating the bags to bring the top level of the contents of each bag to a predetermined pack line. This additional elevating of the bags takes care of variations in pack height due to variable factors so that the upper level of the contents for all bags at subsequent stations will be uniform.

A more specific object is to provide mechanism capable of rapid adjustment by the operator and which will function to elevate the movable bottoms of the bag carriers to adjust the bags to an initial pack height.

Another object resides in the provision of novel mechanism which will operate automatically to elevate the movable bottoms of the bag carriers from their position following the initial pack height adjustment to move the material in each bag into contact with means determining the constant pack line, or in other words, the upper working level of the bag machine. This automatic gauging takes care of any variation in

pack height due to small density changes in the product or other variable factors.

A further object of the invention resides in the provision of locking means for locking the movable bottoms of the bag carriers and which can be held released during the operation of the initial pack height adjuster and also during operation of the automatic gauging mechanism.

With these and various other objects in view, the invention may consist of certain novel features of construction and operation, as will be more fully described and particularly pointed out in the specification, drawings and claims appended hereto.

In the drawings which illustrate an embodiment of the device and wherein like reference characters are used to designate like parts—

Figure 1 is an elevational view illustrating the improvements of the invention, and wherein the bag carrier pockets are shown in four different positions corresponding to four different stations of the bag machine; and

Figure 2 is a vertical sectional view taken substantially through the center of the mechanism occupying station No. III.

Referring to the drawings, the bag machine to which the improvements of the invention may be applied is indicated as including structural parts 10, 11 and 12, the parts 10 and 12 forming part of the frame of the machine, whereas, part 11 may comprise an upper platform providing a support for mechanism which may have location at other stations of the bag machine. In machines of the general class referred to the bags are supported individually by carrier pockets, one side of each pocket being open to permit a bag to be placed within the pocket and to be removed therefrom following the closing operation.

In accordance with the invention the carrier pockets comprise a back plate 14, Figure 2, a pair of side plates 15, and a displaceable bottom plate 16. The bag 17 is disposed within the space formed by these four members. The back plate 14 is fastened to a support block 18 adapted to have sliding movement horizontally of the machine, which movement is effected by the conveyor comprising the roller chain 20. Said chain, which may be of any conventional construction, has lugs 21 extending therefrom at intervals throughout its length and which lugs project beyond the recess 22 confining said chain. The sides 15 of the carrier pockets are fixed to L-shaped members 23, the rear ends of which are guided for translating movement by a groove formed in block 18. The pins 24 extend rear-

wardly from the members 23 and provide connecting means for the forked end of bell cranks 25 and 26, respectively. Said pins 24 are joined by a tension spring 27 which passes through a clearance opening in the block 18 and accordingly the side plates 15 of the carrier pockets are resiliently drawn toward each other, the translating movement of said plates being permitted as a result of the guided support of the rear ends 10 of members 23. The function of the bell cranks 25 and 26 is to control the movement of the side plates and accordingly the bell cranks are pivotally supported at 28 to a bar 29 fixed to the back plate 14. The inwardly directed ends of the bell 15 cranks are pivotally connected by pin 31.

A roller 32 is carried by said pin 31 and when said roller is in contact with the stationary cam 33 the inwardly directed ends of the bell cranks are horizontally positioned to maintain the side 20 plates 15 in separated relation, affording easy entrance of a filled bag into the carrier pockets. This will be evident from an inspection of station I, Figure 1. However, when said carrier pocket has moved to station II, roller 32 will have 25 passed out of contact with stationary cam 33 and the tension spring 27 will be effective to hold the side plates in contact with the sides of the bag.

The bottom plate 16 of each carrier pocket is 30 fixed to the horizontally disposed leg 34 of an L-shaped bar having a vertically disposed leg 35, which latter is supported by the guides 36 fixed to the back plate 14 for vertical movement to thereby elevate or lower the bag as desired. 35 Means for locking leg 35 to hold the displaceable bottom plate 16 in adjusted position is provided by the locking lever 37 pivoted to the back plate 14 at 38 and yieldingly biased in an upward direction by spring 39 fixed to the projecting arm 40. The outer projecting end of lever 37 carries a roller 41 adapted to contact the underside of the fixed cam bar 42. This cams the lever 37 to rotate the same counter-clockwise, with the result that the inwardly directed end of said lever is released from contact with leg 35 and accordingly said leg and the displaceable bottom of the carrier pocket may be elevated or lowered as desired.

The release of the displaceable bottom plate of 50 the carrier pocket takes place when the same reaches station I, Figure 1. Leg 35, carrying the roller 43 at its lower end, will drop to its lowermost position, whereupon said roller will contact the riser bar 44 having the end located under station I, slotted at 45, which slot receives the 55 stud 46 for supporting said end of the bar while permitting limited pivoting and adjusting movement of said bar. The other end of the bar 44 is pivotally fixed to stud 47 projecting from the plate 48, which is constrained by the guides 49 for vertical movement on slide 50. As better shown in Figure 2, the slide 50 is suitably supported from the frame 12 of the machine. Vertical movement of the plate 48 is obtained by 60 turning the crank 51 fixed to shaft 52 suitably journalled in the frame 12 of the machine and rotating pinion 53 having engagement with rack 54 fastened to plate 48. The pawl 55, actuated by lever 56, locks the rack in position. It will 65 be evident from the foregoing description that by turning crank 51 the riser bar 44 may be set at any desired inclination so as to elevate the displaceable bottom 16 of the carrier pocket to any predetermined level as said pocket is intermittently propelled from station I to station III.

The structure above described comprises means adapted to be set by the operator for elevating the bags to an initial pack height. The adjustment can be readily changed by actuation of the crank 51, which elevates the plate 48 and thus changes the inclination of the riser bar 44. For exact gauging of the upper pack level the invention provides means for automatically elevating the bag from the initial pack height until the level of the contents within the bag is in engagement with a plunger which determines a constant pack line or, in other words, the working level of the bag machine. The automatic means essentially consists of a lifter bar 58, Figure 2, supported for vertical reciprocation on the plate 15 10 48 by the guides 60 and 61. The lifter bar 58 is so located on the plate 48 that said bar has contact with roller 43 when the carrier pocket is located at station III. Movement of the plate 48 vertically of the slide 50 will effect vertical movement of the displaceable bottom of the carrier pocket. However, this can be accomplished independently of the plate 48 by the lifter bar 58 which is automatically actuated by means to be presently described for accurately gauging the 15 upper level of the pack.

The stud 62 projecting from the lifter bar 58 journals a lever 63 which pivotally connects at its upper end with a lever 64 fixed to shaft 65 suitably journalled by plate 48. The end of shaft 65 20 opposite lever 64 has fixed thereto lever 66, the lower end of which carries a roller 67. Engaging said roller is a lifter cam 68, the vertical length of its working face being such that the roller 67 25 will always remain in contact within the range 30 of vertical adjustment of the plate 48. The lifter cam is suitably supported for horizontal movement by bracket 69, it being understood that said lifter cam is reciprocated by means not shown forming part of the bag machine. 35

As the carrier pocket travels from station II to station III the roller 43 will leave the riser bar and ride on the upper surface of the lifter bar 58 and guide 60. As the carrier pocket comes to rest at station III the plunger 70 will descend to its 45 lowermost position indicated by 70', shown in dotted lines in Figure 1. This lowermost position of the plunger will determine a constant pack line, that is, the upper level of the material within the bags. In timed relation with the 50 descent of the plunger 70 the lifter cam 68 is yieldingly actuated in a direction toward the right, Figure 1, into contact with the roller 67. This causes rotation of the levers 66 and 64 to lift the bar 58 a predetermined maximum distance, for example, one inch. By means of the roller 43 in contact with said bar the displaceable bottom plate 16 of the carrier pocket is also elevated to bring the upper level of the material in the bag into contact with plunger 70. This prevents further rise of the elevating mechanism but since the lifter cam is yieldingly actuated damage to the parts is prevented. 55

The right hand end of the fixed cam bar 42 terminates as shown in advance of station III. 60 The extension 72 is pivoted to said terminating end and in order to provide for vertical pivoting movement of said extension the same is supported by the toggle means indicated generally by numeral 73 and actuated by shaft 74, which is rotated by the bag machine. In normal position the extension 72 of the cam bar is horizontally disposed, thus maintaining the locking lever 37 released and allowing movement of the leg 35 supporting the displaceable bottom of the carrier 65 70 75

pocket. Immediately upon completion of the gauging operation the toggle is broken and the extension 72 will assume its uppermost position, permitting the locking lever 37 to rise as a result 5 of the tension applied thereto by spring 39. This action of the locking lever will lock the leg 35 and the bag within the carrier pocket in gauged position. The plunger 70 then rises to its upper 10 position and the lifter bar 58 will drop as a result of rearward movement toward the left, Figure 1, of the lifter cam 68. The gauged carrier pocket is then carried forward by movement of the roller chain 20 to the next station where other operations are performed on the bag. However, 15 this movement of the conveyor mechanism brings another carrier pocket to station II and the automatic gauging will be repeated with respect to this carrier pocket.

The pack height adjuster of the invention can 20 be readily set by the operator merely by turning the crank 51 to thereby cause elevation of the bags to an initial pack height as the carrier pockets move from station I to station III. Following this adjustment of the bags the automatic 25 gauging mechanism is operative to further elevate the bags bringing the contents into engagement with the plunger 70. This takes care of any variation in pack height due to small density changes or other variable factors.

30 The invention is not to be limited to or by details of construction of the particular embodiment thereof illustrated by the drawings, as various forms of the device will of course be apparent to those skilled in the art without departing from 35 the spirit of the invention or the scope of the claims.

What is claimed is:

1. In a packaging machine, conveyor mechanism having intermittent movement, a plurality 40 of bag retaining receptacles supported by said mechanism and each including a displaceable bottom member, means for elevating the displaceable bottom members as the receptacles traverse the length of said means to locate the bottom 45 members a distance below a predetermined constant pack line, and automatic mechanism additionally elevating said bottom members to bring the top level of the contents of each individual bag up to said constant pack line.

50 2. In a packaging machine, conveyor mechanism having intermittent movement, a plurality of bag retaining receptacles supported by said mechanism and each including a displaceable bottom member, means for elevating the displaceable bottom members as the receptacles traverse the length of said means to locate the bottom 55 members a distance below a predetermined constant pack line, manually actuated means for adjusting said elevating means, and automatic mechanism additionally elevating said bottom members to bring the top level of the contents of each individual bag up to said constant pack line.

60 3. In a packaging machine, conveyor mechanism supporting a plurality of receptacles and 65 having intermittent movement for successively locating said receptacles at various stations, each of said receptacles including a displaceable bottom member, means extending for a plurality of stations for elevating the displaceable bottom members to locate the bags retained by their receptacles a distance below a predetermined constant pack line, and automatic mechanism located at the terminal end of said elevating means for 70 additionally elevating the bottom members to 75

bring the top level of the contents of each individual bag up to said constant pack line.

4. In a packaging machine, conveyor mechanism supporting a plurality of receptacles and having intermittent movement for successively 5 locating said receptacles at various stations, each of said receptacles including a displaceable bottom member, releasable locking means for retaining each bottom member in adjusted position, a riser bar extending for a plurality of stations for 10 elevating the displaceable bottom members to locate the bags retained by their receptacles a distance below a predetermined constant pack line, automatic mechanism located at the terminal end of said elevating means for additionally elevating 15 the bottom members to bring the top level of the contents of each individual bag up to said constant pack line, and cam means for holding said locking lever released during the mean pack height adjustment and said automatic gauging. 20

5. In a packing machine, conveyor mechanism supporting a plurality of receptacles and having intermittent movement for successively locating 25 said receptacles at various stations, each of said receptacles including a displaceable bottom member, means extending along the path of the receptacles for elevating the displaceable bottom member of the receptacles successively, and manually actuated means for adjusting the inclination 30 of said elevating means.

6. In a packaging machine, conveyor mechanism supporting a plurality of receptacles and having intermittent movement for successively locating 35 said receptacles at various stations, each of said receptacles including a displaceable bottom member, a riser bar extending along the path of said receptacles for a plurality of stations, said bar elevating the bottom member of said receptacles at said stations, and manually actuated means for adjusting the inclination of said bar. 40

7. The method of elevating filled bags to their proper pack height determined by the material within the bag which consists in elevating said bags to an initial pack height whereby the material within the bags will be located a distance below a predetermined constant pack line, and then additionally elevating each bag to bring the top level of the contents of each individual bag up to said constant pack line thereby accurately 45 gauging the upper pack level of the material. 50

8. In a method of packaging material in bags, the steps which consist in intermittently moving the bags to successively locate them at various stations, elevating the bags gradually to an initial pack height whereby the material within the bags will be located a distance below a predetermined constant pack line, and then additionally elevating the bags to bring the top level of the contents of each individual bag up to said constant pack line to thereby accurately gauge the 55 upper pack level of the material, said additional elevation of the bags taking care of variations due to small density changes in the material and other variable factors. 60

9. In a packaging machine, conveyor mechanism supporting a plurality of receptacles and having intermittent movement for successively locating 65 said receptacles at various stations, each of said receptacles including a backing plate fixed to the conveyor mechanism, and a pair of side 70 plates movably associated therewith, actuating means connecting with said plates for moving the plates to increase or decrease the distance therebetween, means yieldingly biasing said plates in a direction toward each other, and cam means 75

at one of said stations positioned to engage said actuating means to cause said side plates to move apart a predetermined distance against the tension of said yielding means.

5. 10. In a packaging machine, conveyor mechanism supporting a plurality of receptacles and having intermittent movement for successively locating said receptacles at various stations, each of said receptacles including a backing plate fixed 10 to the conveyor mechanism, a pair of side plates movably associated therewith, and a displaceable bottom member associated with said backing plate and with said side plates, actuating means connecting with said plates for moving the plates 15 to increase or decrease the distance therebetween, means yieldingly biasing said plates in a direction toward each other, and cam means at one of said stations positioned to engage said actuating means to cause said side plates to move apart 20 against the tension of said yielding means.

11. In a packaging machine, conveyor mechanism supporting a plurality of receptacles and having intermittent movement for successively locating said receptacles at various stations, each of said receptacles including a backing plate fixed 5 to the conveyor mechanism, a pair of side plates movably associated therewith, and a displaceable bottom member associated with said backing plate and with said side plates, actuating means connecting with said plates for moving the plates 10 to increase or decrease the distance therebetween, means yieldingly biasing said plates in a direction toward each other, cam means at one of said stations positioned to engage said actuating means to cause said side plates to move apart 15 against the tension of said yielding means, and releasable locking means holding the bottom member in adjusted position vertically of the receptacle.
